Attorney

UNITED STATES PATENT OFFICE.

ELMER S. GROSS, OF MILWAUKEE, WISCONSIN.

SHAFT-GUARD.

1,209,959.

Specification of Letters Patent. Patented Dec. 26, 1916.

Application filed May 29, 1916. Serial No. 100,644.

To all whom it may concern:

Be it known that I, ELMER S. GROSS, a citizen of the United States, residing at Milwaukee, in the county of Milwaukee and 5 State of Wisconsin, have invented certain new and useful Improvements in Shaft-Guards, of which the following is a specification, reference being had to the accompanying drawings.

10 This invention relates to devices for protecting persons from contact with revolving shafting or other revolving bodies of like character, and particularly to devices adapted to be placed upon the shafts themselves 15 and which will act as shields or guards so as to protect the clothing of a person from getting caught on the shaft.

The danger from revolving shafts is very well known. Many accidents occur every 20 year due to unprotected shafting, but it is usually supposed that a perfectly smooth shaft without projections, set screws, bolt heads or key-ways, is relatively safe, but I have found by experience that the pitchy 25 scale composed of oil and dust on the shaft is sufficient to frictionally engage the clothing of a workman and to wind the clothing upon the shaft and that even a perfectly clean polished shaft will engage and wind 30 articles of clothing thereon. These perfectly clean shafts are particularly dangerous, therefore, for the reason that a workman will take more chances with a smooth shaft than he will with one which has projections 35 and is therefore more liable to be caught and injured by these shafts than by shafts which are apparently more dangerous.

The general object of my invention is to provide a very simple, cheap and effective 40 means for safe-guarding the lives of those working around revolving shafting or other revolving bodies, and particularly to provide a device which may be attached to line shafting or end shafting, which may be 45 readily applied, readily removed, which is very cheap and which will positively prevent the contact of the workmen's clothing with the shaft itself.

A further object of the invention is the 50 provision of a device of this character which surrounds the shaft and forms a shield and

which while rotating with the shaft under normal conditions is held from rotation by any pressure brought against it.

Still another object is to so construct this 55 protecting shield that it will relatively closely embrace the shaft so that there is no chance of the clothing being drawn into the space between the shield and the shaft itself.

60 A further object of the invention is the provision of a device which may be applied to the ends of shafting to cover the ends, and in this connection to attach it to the end shafting by means of a screw or other fastening device which will permit its free rotation relative to the shafting.

Other objects will appear in the course of the following description.

My invention is illustrated in the accompanying drawings, wherein:

Figure 1 is a side elevation of a section of line shafting with my protector applied thereto; Fig. 2 is a section on the line 2-2 of Fig. 1; Fig. 3 is an elevation of the end 75 of a shaft showing my protector applied thereto; Fig. 4 is a longitudinal sectional view of the shaft and protector; Fig. 5 is an end view of the shafting and protector; Figs. 6, 7 and 8 are fragmentary longitudinal sectional views of the shaft ends showing different ways of mounting the protector upon the shaft end.

Referring now to Fig. 1, 10 designates a line shafting which for the purpose of illustration is shown as carrying a pulley 11 and as being mounted in a hanger 12. Disposed around this shaft 10 is a coil of soft wire 85 designated 13. This wire is shown at one end as bearing against the pulley 11 and at 90 the other end as bearing against a split collar 14 which is loosely mounted upon the shaft. The coil of wire 13 embraces the shaft closely and normally rotates therewith. Preferably the space between the coils 95 is equal to the width of the wire used in making the coils, but other proportions may be used. Preferably, also, in order to give freedom to the coil, the coil is cut at one or more points as at 15. This wire coil is put 100 on the shaft in one continuous piece, that is, one continuous coil extending between two

pulleys or two hangers or between a pulley and a hanger. The coil is then cut into sections, as at 15, the purpose of thus cutting it being to cause the coils to be more free 5 on the shaft. This coil, or coils, provides what may be termed a sleeve that will normally revolve with the shaft but is held from rotation by any pressure against it, as for instance, the workman leaning over the 10 shaft with his clothing in contact with the coil. The purpose of the split collar 14 is to prevent any frictional engagement between the hanger 12 and the extremity of the coil and to prevent the coil from cutting 15 into the hanger. The coil will preferably have a slight tension on the ends just enough to keep it from rattling or causing any noise. It will be obvious now that if a workman comes in contact with the coil and bears 20 against the shaft, the coil will be held from rotation and will support the workman's clothing away from the face of the shaft and thus establish perfect safety for the workman.

25 While in Fig. 1, I have illustrated my invention as applied to a line shaft, it is also equally applicable to the ends of shafts. Thus for instance, in Fig. 3, I have shown the end of the shaft 16. The extremity of 30 this shaft is bored, as at 17, for engagement by a screw 18 having a relatively large head. A washer 19 is placed upon the end of the shaft and this washer has a central bushing or hub 20 which acts as a spacer. The coil 35 21 which is of soft wire and which may be of any length desired, extends spirally around the shaft in more or less intimate contact therewith, and at its outer extremity the coil is bent, as at 22, so as to extend across the end of the shaft to the center 40 thereof and then is formed with an eye 23 which embraces the bushing 20. It will thus be seen that while the screw 18 may revolve with the shaft, the coil does not necessarily 45 revolve with the shaft but that if pressure be brought upon the coil it will be held from such rotation and act in exactly the same manner as the coil heretofore described. I have illustrated the screw 18 as a safety 50 screw and as formed with a socket 24 for the application of a wrench in place of being formed with a nick as the last-named form of screw is deemed to be dangerous. It will be obvious that other types of screws may be 55 used and in Fig. 6 I have illustrated a screw 18^a which is only insertible for a certain depth into the shaft and which the eye 20 surrounds. In Fig. 7 a slightly different form of screw 18^b is shown which has a solid shoulder spacing the head of the screw from 60 the end of the shaft. In Fig. 8 I show the construction which must be used where a lathe center is found in the end of a shafting. In this case a thin metal bushing 25

must be cut the proper length and disposed 65 around the screw so as to establish the proper distance between the face of the shaft and the inner face of the screw head. This adjustment of the screw should be accurately made so as to avoid any noise by the 70 end washer 26 and the coil. These end coils, as above described, may be made and carried in stock, but the coils which are disposed upon line shafting should be coiled on the shaft in place. This, however, is such a simple matter that the cost of material and labor 75 will be small as compared with the danger the device removes. In addition to acting as a safety appliance this floating sleeve or bushing formed by the coils 13 or 21 will 80 prevent belts from being burned in case they run off from a pulley and allowed to hang on the shaft for any length of time. The use of this sleeve formed of the coil of wire is not confined to shafting but may be applied to any revolving body such as shaft 85 couplings, drums, etc. The floating sleeve may also be constructed of other material than wire, but I regard wire as being best for this purpose and as being particularly 90 cheap and convenient to install. It will be seen that this protector or shield takes up no shop space as do many other safety guards, it needs no other support than the shafting, and in case an additional pulley is 95 to be put on the shaft already equipped with the coiled sleeve it is only necessary to cut a portion of the coil out at the proper point. It will be seen that this sleeve does not interfere with the access to the shaft, that it 100 takes up no valuable room, but that it provides an absolute guard which is, as it may be termed, automatically thrown into operation the minute it is needed. As it normally revolves with the shafting it does not 105 interfere with the power delivered by the shafting.

Having described the invention, what I claim is:

1. The combination with a shaft end, of a 110 protector comprising a closely coiled sleeve surrounding the shaft end, a member projecting from the axial center of the shaft end, the extremity of the coil forming the sleeve being rotatably engaged with said member.

2. The combination with a shaft end, of a 115 protector therefor comprising a coil of soft wire loosely surrounding the shaft, one end of the wire being bent across the shaft end 120 and formed with an eye, and a fastening device passing loosely through the eye and into engagement with the shaft at its axial center.

3. The combination with a shaft end, of a 125 protector therefor comprising a coil of soft wire loosely surrounding the shaft, one end of the wire being bent across the shaft end 130 and formed with an eye, and a screw pass-

ing into the shaft at its axial center, the screw having a head, the screw passing through the eye of the coil, and means being provided to space the head from the end of 5 the shaft to permit the free rotation of the coil with relation to the screw and shaft.

In testimony whereof I hereunto affix my signature in the presence of two witnesses.

ELMER S. GROSS.
